UNITED STATES PATENT OFFICE

2,285,197

FEEDING UNIT FOR TABULATING MACHINES

John E. Euth, Chicago, Ill., assignor to United Autographic Register Co., a corporation of Illinois

Application January 6, 1941, Serial No. 373,372

6 Claims. (Cl. 197—133)

This invention relates to stationery feeding and aligning devices for use in feeding stationery over the platen of tabulating machines, Addressograph machines, and the like.

The primary object of the invention is to provide a simple and compact feeding unit which is carried by the cross rods of a machine and has its own guiding and adjusting mechanism.

A further object of the invention is to provide an improved mounting for the guide member whereby it may be locked in operative position, but readily released and held out of the way during a loading operation.

Another object of the invention is to provide a simple built-in adjusting device whereby the unit may be slid quickly to a position near its final position and then adjusted accurately to final position. In typewriting machines of this type it will be understood that it is every essential to have the feed mechanism and its vertical guides aligned very accurately with respect to the platen of the machine.

The invention is illustrated in a preferred embodiment in the accompanying drawing, in which—

Figure 1 is a broken angular plan view of an attachment embodying the invention; Figure 2, a broken side elevational view of the feed mechanism mounted on the tie rod and shafts of the frame; Figure 3, a sectional view of the adjusting mechanism, taken as indicated at line 3 of Figure 2; Figure 4, a sectional view, taken as indicated at line 4 of Figure 3; and Figure 5, a perspective view of the cap which confines the split-nut.

The invention is illustrated as applied to an attachment for a tabulating machine. This attachment may be placed on a standard tabulating machine and held in position without the use of any bolts, clamps or other securing means. In the ordinary tabulating machine, as illustrated in Jensen Patent No. 2,130,015, the attachment is driven from a gear on the platen roll of the machine. By suitable gearing the drive shaft of the attachment is rotated in timed relation to the platen roll and drives the conveyer members equipped with register pins to engage in perforations in the stationery.

In the present device end frames 6 and 7 are provided at their lower ends with U-shaped keepers 8 and 9 which fit over and engage supporting parts on the tabulating machine to hold the device in position. A gear housing 10 is provided at the lower end of the frame member 7 and contains a train of gears 11 which drives

a rotatable square shaft 12 in well known manner. A threaded shaft 13 is carried by the members 6 and 7 and serves to position the feeding unit in the frame. A tie rod 14 clamps the members 6 and 7 together in proper spaced relationship and also serves as a transverse guide for supporting one end of the feeding unit.

In Figure 1 only one feeding unit is illustrated, but it will be understood that one or more similar units may be provided and supported in the same manner. The feeding unit has a sheet metal housing 15 made up of two parts 15a and 15b which are held in spaced relation leaving a slot 16 through which the feed pins 17 extend. A sprocket wheel 19 is journaled in the lower end of the housing and is provided with a star shaped socket 20 which makes a splined engagement with the driving shaft 12. An idler pulley 21 is journaled in the upper portion of the housing 15 on a stub shaft 22. A link belt 23 is carried by the wheels 19 and 21 and carries a continuous series of feed pins 17. The upper end of the housing is provided with fixed guides 24 which disengage the pins from perforations in the stationery as the pins pass therebetween.

An adjusting device 25 is journalled in the housing 15, as shown in Figure 3, and has an enlarged head 26 which is slotted to receive a half-nut 27 provided with a cut-away clearance opening 28. The nut is urged into threaded engagement with the shaft 13 by means of a spring 29 which bears against a flange 30 and has a closure cap 31 held in position by screws 32. The nut has an outwardly extending portion 33 which may be depressed so that the entire unit may be slid along the cross rods of the device to a desired position. The finger piece is then released and by rotating the head 26 bodily, a very accurate adjustment of the feeding unit with respect to the frame may be readily obtained. A compression spring 34 merely increases the friction to resist rotation and change in position of the housing.

A slotted guide member 35 is pivotally mounted on the stub shaft 22 by means of a slot 36 and is held in position by a nut 37. The guide member has a slotted portion 38 which is adapted to hold the stationery in engagement with the pins 17 when in operative position, as shown in Figures 1 and 2. One end of the guide member has a hook shaped finger 39 which is adapted to engage the shank of a cap screw 40. The other end of the guide member is cut to form a curved sector 41 and the guide member is urged bodily into

locking position by means of a crank 42 acted upon by a tension spring 43.

Thus it will be understood that when it is desired to swing the guide member out of operative position to facilitate loading, it is merely necessary to pull the guide member downwardly against the action of latch 42 and swing it upwardly about the pivot 22. The spring pressed latch 42 will bear against the sector 41 so as to hold the guide member up in an out of the way position. To return the guide member to latching position it is merely necessary to press it down firmly and the hook 39 will snap over the cap screw 40.

On the opposite side of the housing is a fixed plate 44 which is slotted, as indicated at 45, to make slidable connection with the tie rod 14. Thus it will be understood that the housing is supported by the tie rod 14 and the screw shaft 13.

If desired, the screw shaft 13 may be mounted so as to be rotatable and a crank provided at one end. Thus rotation of the shaft 13 will cause the housing to move laterally. However, it is preferred to have the threaded shaft fixed against rotation so that it may also serve as a tie rod for the frame.

The foregoing detailed description has been given for clearness of understanding only, and no unnecessary limitations should be understood therefrom for some modifications will be obvious to those skilled in the art.

I claim:

1. A stationery feeding and aligning unit, adapted to be carried by the frame of a machine, comprising: a housing provided with a pair of pulleys carrying an endless belt conveyer provided with outwardly extending register pins; a guide member to direct stationery into feeding engagement with said pins, said guide member being pivotally mounted on a shaft extending through the housing to permit it to be turned away from operative position to facilitate loading; and spring-held latching means for releasably holding the guide in operative position.

2. A device as specified in claim 1, in which the pivotal connection of the guide member is of the pin-and-slot type, the guide member has a hook which is adapted to engage a stud on the housing, and a spring urges the guide member bodily into locked position.

3. A device as specified in claim 1, in which the pivotal connection of the guide member is of the pin-and-slot type, the guide member has a hook which is adapted to engage a stud on the housing and the guide member also has a curved sector frictionally engaged by spring means, said means urging the guide member bodily into latched position when the latter is in operative position, and frictionally engaging the curved sector to hold the member out of the way when moved to inoperative position.

4. A laterally adjustable feeding and aligning unit, on the frame of a typewriting machine attachment having a driving shaft and a threaded shaft, comprising: a housing provided with a pair of pulleys carrying endless belt conveyers provided with outwardly extending feed pins, one of said pulleys being hollow and making a splined driving connection with the driving shaft; and 15 positioning means journalled in said housing including a nut releasably engaging the threaded shaft of the frame and rotatable bodily to move the housing on said shafts.

5. A device as specified in claim 4, in which 25 the nut has its threads cut away and the opening enlarged in one portion, and the threaded portion is urged into engagement with the threaded shaft by means of a spring, said nut having an outwardly extending finger piece which is compressible to release threaded engagement with the shaft.

6. A laterally adjustable feeding and aligning unit, on the frame of a typewriting machine attachment having a rotatable driving shaft, a threaded shaft and a tie rod, said unit comprising: a housing in which is journalled a pair of pulleys carrying an endless belt provided with outwardly extending feed pins, one of said pulleys being hollow and making a splined driving 30 connection with the driving shaft; a guide plate fixed to said housing to support the housing for lateral movement on the tie rod of the frame; a movable guide member pivotally mounted coaxially with one of the pulleys and having a slot 35 through which the pins may travel while engaging stationery strips; and positioning means journalled in said housing including a split-nut releasably engaging the threaded shaft of the frame and being rotatable bodily to move the 40 housing with respect to said frame.

JOHN E. EUTH.
